UNITED STATES PATENT OFFICE

FREDERICK OERTLY, OF PHILADELPHIA, PENNSYLVANIA, ASSIGNOR TO JOHN BROMLEY & SONS, OF SAME PLACE.

DESIGN FOR CARPET.

Specification forming part of Design No. 11,448, dated October 7, 1879; application filed September 8, 1879.
[Term of patent 3½ years.]

To all whom it may concern:

Be it known that I, FREDERICK OERTLY, of the city and county of Philadelphia, Pennsylvania, have invented a certain new and Improved Design for Carpets, of which the following is a specification.

The nature of my invention is fully set forth in the accompanying photographic illustration, to which reference is made.

What I claim as new, and desire to secure by Letters Patent, is—
The design for carpets, as shown.

FRED. OERTLY.
